WILLIAM A. CLARK, OF WOODBRIDGE, CONNECTICUT.

Letters Patent No. 93,807, dated August 17, 1869.

IMPROVEMENT IN COUNTERSINK AND BIT.

The Schedule referred to in these Letters Patent and making part of the same

To all whom it may concern:

Be it known that I, WILLIAM A. CLARK, of Woodbridge, in the county of New Haven, and State of Connecticut, have invented a new Improvement in Combined Countersink and Bit; and I do hereby declare the following, when taken in connection with the accompanying drawings, and the letters of reference marked thereon, to be a full, clear, and exact description of the same, and which said drawings constitute part of this specification, and represent, in—

Figure 1, a side view, looking toward the edge of the spur;

Figure 2, the same turned one-fourth around;

Figure 3, the same turned another fourth around;

Figure 4, the bit detached;

Figure 5, the counterbore detached; and in

Figure 6, the bit with the centre-bore inverted, so as to serve as a plug-cutter.

This invention relates to an improvement in combined bit, countersink, and counterbore; and

It consists—

First, in the arrangement of a countersink or counterbore over a bit, the bit constructed so that the throat of the counterbore will always conform to the throat or twist of the bit.

Second, in forming the counterbore or countersink with a plug-cutter, in one and the same piece.

To enable others skilled in the art to construct and use my improvement, I will proceed to describe the same as illustrated in the accompanying drawings.

A is a boring-instrument, commonly called a gimlet-bit.

The part B, extending from the bit A to the shank C, is of an equal diameter, the bit being tapering, as in common gimlet-bits, and the shank so as to be fitted to a common brace.

D is the counterbore, which consists of a cylinder, formed so as to pass on to the part B; and at its lower end a cutter, a, is formed, and a spiral throat, d, extending from the cutter around the cylinder D, the twist conforming nearly to that of the twist of the bit; and upon the edge of the throat, opposite the cutter a, is formed a spur, f, to cut in advance of the cutter a.

The shape of the cutter a is such that it will cut a seat for the screw-head to set into, in similar manner as common countersinks.

The cylinder D is set on over the bit, as seen in fig. 1.

A set-screw, E, passes, through the cylinder, into the spiral groove b, (see fig. 4,) so that the throat d, of the cutter a, will conform to the throat or twist of the bit below, as seen in fig. 1. This forms a channel for the passage of the chips both from the bit and counterbore, and the groove b, conforming to the twist of the bit, will always hold the throat of the counterbore in the same relative position, at whatever height it is placed from the point.

Over the cylinder is arranged a stop, G, set upon the cylinder D, so as to arrest the operation of the bit, when the required depth is bored, the guide passing over the throat, so as in no way to stop the throat.

It will be observed, that for different-sized screws, different-sized bits will be required, and different-sized counterbores may be applied to the said instrument.

As a plug-cutter—that is, an instrument for cutting a plug to fill in over the screw-head—I construct upon the other end of the cylinder D a cutter, L, in the form of a segment of a circle, the inner diameter of which corresponds to the diameter of the cutter-end of the cylinder.

To use this cutter, I invert the cylinder, as seen in fig. 6, placing it upon the same bit, and changing the set-screw E from the position seen in fig. 5 to the other end, as seen in fig. 6. Then the plug-cutter is used in like manner as other plug-cutters.

Having fully described my invention,

What I claim as new and useful, and desire to secure by Letters Patent, is—

In combination with the counterbore, made adjustable in a bit, the plug-cutter L, formed in one and the same piece with the counterbore, and so as to be applied to the bit, substantially as set forth.

WM. A. CLARK.
